CALCULATING DEVICE

William F. Shaw, Rocky River, Ohio, assignor of
one-half to Horace C. Mayers, Rocky River,
Ohio

Application August 7, 1941, Serial No. 405,819

5 Claims. (Cl. 235—83)

This invention relates to calculating devices, and more particularly, to rotatable dial type calculators.

An object of this invention is to provide a relatively small and compact calculating device which provides a relatively large number of problems and answers.

Another object is to provide a relatively simple and easily operable calculating device, which may be used by school children in mastering the fundamental combinations in additions, subtractions, multiplication, and division.

Other objects are to provide a calculating device having a minimum number of parts and numerals the same being easily assembled and capable of being produced at a relatively low cost and adaptable for many different numerical computations.

These and other objects will be apparent during the course of the following specification.

In the drawing forming a part of this specification:

Figure 1 is a plan view of one of my dial calculators, with parts broken away,

Figure 2 is a central vertical section taken on the line 2—2 of Figure 1, while

Figure 3 is a broken fragmentary view of a portion of my computing chart.

My calculating device, indicated generally by the numeral 11, comprises an inner dial 12 formed of suitable material such as cardboard, or any other material capable of being printed on, disposed between two similar circular dials 13a and 13b, a hollow rivet 14 having flanged portions 15 on each end thereof serving to retain the dials together and permit them to be rotated around the rivet 14 as hereinafter disclosed.

The diameter of the inner dial 12 is slightly larger than the diameters of the cooperating dials 13a and 13b so that it projects beyond the outer margins of the dials 13a and 13b. The outer margin of the inner dial 12 is preferably provided with a series of cut out portions 16, as shown in Figure 1, which facilitate the grasping and turning of the inner dial by the fingers of the operator.

As illustrated in Figures 1 and 3 it will be observed that the inner dial 12 is provided with four concentric circular rows of numerals indicated by the numerals 17, 18, 19, and 20, the numeral 17 indicating the inner row, the numeral 20 indicating the outer row, while the numerals 18 and 19 indicate the intermediate row of numerals. A close inspection of Figures 1 and 3 will disclose that the numerals in rows 17 and 19 are positioned and arranged in such a manner that each numeral of each of the rows 17 and 19 is aligned with the radius of the inner dial 12, while the numerals in rows 18 and 20 are

not aligned with such radius, but are aligned with a vertical line at one side of the center of the dials indicated by the numeral 21.

Each of the outer dials 13a and 13b is provided with two sets of problem apertures 22a and 22b, permitting numerals on the dial 12 to be viewed therethrough, said apertures being horizontally aligned. The right hand problem aperture 22a, as viewed in Figure 1, is aligned with the inner row of radially aligned numerals 17, while the left hand problem aperture 22a is aligned with the next row of numerals 18 which are not radially aligned. The combination of the horizontal disposition of the problem apertures 22a and the disposition of the numerals in rows 17 and 18 on the inner dial 12 presents the numerals constituting the problem in a horizontal alignment, thus permitting the problem to be quickly and easily read. This would not be true were the problem apertures 22a disposed at a uniform distance from the center of the dial or were the rows of numerals 17 and 18 each radially aligned.

Problem apertures 22b are also horizontally aligned but differ from the problem apertures 22a in being aligned with rows of numerals 19 and 20 on the inner dial 12. It will be noticed that one of the problem apertures 22b is aligned with radially disposed row of numerals 19 and the other is aligned with non-radial row of numerals 20.

Answer apertures 23a and 23b are also provided in dials 13a and 13b. It will be noticed that answer aperture 23a is aligned with the outer row of numerals 20 on the inner dial 12, while answer aperture 23b is aligned with next to the inner row of numerals 18, so that the answer numerals always show a numeral non-radially aligned.

Indicia indicating one of the particular problems such as addition, subtraction, multiplication, and division is printed near each group of problem apertures, the word "multiply" being provided between problem apertures 22a and the word "divide" being provided between the problem apertures 22b. Dial 13b is similarly provided with problem and answer apertures relating to addition and subtraction and operates in a similar manner, as will be readily understood.

There is a definite mathematical relationship between the problems of multiplication and division, hence these problems are grouped on the dial 13a, while a similar relationship between the problems of addition and subtraction results in their being grouped on dial 13b.

The calculating device 11 is used in an obvious manner. For example, to set up the problem shown through problem apertures 22a in Figure 1, the user grasps the device between the thumb and the middle finger and rotates the inner dial

12 with the index finger, until the numeral 8 indicating the multiplicand appears in the left hand problem aperture 22a, and the numeral 4 indicating the multiplier appears in the right hand aperture 22a. The product 32 appears through the answer aperture 23a, which may be kept covered by a finger in order to give the user a chance to guess the answer which is disclosed through the answer aperture 23a when the finger is removed.

As shown in Figure 1, when the foregoing problem in multiplication is disclosed through the problem aperture 22a, a problem and answer in division is also set up, in which the numeral 63 indicates the dividend, 7 the divisor, and the numeral 9 appearing through the answer aperture 23b represents the quotient. Thus, it will be seen by arranging the problem and answer apertures and disposing the numerals as indicated, that a material saving of space is accomplished on the inner dial 12, for the reason that each row of numerals 17, 18, 19, and 20 contains one of the figures of a problem, while the same numerals in rows 18 and 20 furnish the answers to the problems, and thus the same numerals serve as problems and answers and provide for the double use of numerals and permits a material saving in the size of the dials.

The dial 13b contains problems in addition and subtraction in which the problems and answers are operated in a similar manner. The device herein illustrated is adapted to be used for many different types of computations and calculations, and thus provides for a relatively wide range of uses. The space around the center of the outer dials 13a and 13b may contain advertising matter, and, as my invention can be produced at a very low cost, it is readily adapted for distribution as an advertising novelty.

If desired, only two dials may be used, and in such case all of the numerals may be placed on one side of the inner dial 12 and four or more pair of problem apertures 22a and 22b may be disposed in the one dial. It is possible to further simplify the device by using rows of numerals 17 and 18 for both multiplication and addition, and in such case it is only necessary to place on the dial 13a the numerals associated with subtraction which appear on the dial 13b.

It will be apparent to those skilled in the art that my invention may be variously changed, used, or modified, without departing from the spirit of the invention or sacrificing the advantages thereof, and that the present embodiment of my invention is illustrative only, and that my invention is not limited thereto.

I claim:

1. In a computing device, a first dial having concentric circular rows of numerals disposed thereon, the numerals in some rows being aligned longitudinally with the radius of the dial, the numerals in other rows being non-aligned longitudinally with said radius and disposed in parallel relation to numerals in said radially aligned row of numerals, and a second dial disposed across said first dial in rotative relation and provided with at least two pairs of spaced apertures, each pair adapted to reveal the cooperating numerals of respectively different problems, and an aperture associated with each pair of apertures and adapted to reveal the answer to

the problem disclosed in its associated pair of apertures, said pairs of apertures and said single apertures being aligned with various rows of numerals in order that the same numerals serve as parts of problems at certain positions of the dials and answers to problems when the dials are in other positions.

2. In a computing device, a first dial having concentric circular rows of numerals disposed thereon, and a second dial disposed across said first dial in rotative relation and provided with at least two pairs of spaced apertures, each pair adapted to reveal the cooperating numerals of respectively different problems, and an aperture associated with each pair of apertures and adapted to reveal the answer to the problem disclosed in its associated pair of apertures, said pairs of apertures and said single apertures being aligned with various rows of numerals in order that the same numerals serve as parts of problems at certain positions of the dials and answers to problems when the dials are in other positions.

3. In a computing device, a first dial having concentric circular rows of numerals disposed thereon, and a second dial disposed across said first dial in rotative relation and provided with at least two pairs of spaced apertures, each pair adapted simultaneously to reveal the cooperating numerals of respectively different problems, and an aperture associated with each pair of apertures and adapted to reveal the answer to the problem disclosed in its associated pair of apertures, said pairs of apertures and said single apertures being aligned with various rows of numerals in order that a numeral in one of said rows serves as part of one of said problems and another numeral in said one of said rows serves as an answer to another of said problems.

4. In a computing device, a first dial having concentric circular rows of numerals disposed thereon, and a second dial disposed across said first dial in rotative relation and provided with at least two sets of spaced apertures cooperable with said rows of numerals, each set comprising a pair of problem apertures and an answer aperture, each pair of problem apertures adapted to reveal the cooperating numerals of respectively different problems, and each answer aperture adapted to reveal the answer to the problem disclosed by the problem apertures of its set, said apertures of said sets being so aligned with said rows of numerals that some of said rows are common to some of the apertures of each set.

5. In a computing device, a first dial having concentric circular rows of numerals disposed thereon, and a second dial disposed across said first dial in rotative relation and provided with at least two sets of spaced apertures cooperable with said rows of numerals, each set comprising a pair of problem apertures and an answer aperture, each pair of problem apertures adapted to reveal the cooperating numerals of respectively different problems, and each answer aperture adapted to reveal the answer to the problem disclosed by the problem apertures of its set, said apertures of said sets being so aligned with said rows of numerals that an answer aperture of one set and a problem aperture of another set are aligned with the same row of numerals.
